UNITED STATES PATENT OFFICE.

LOUIS H. BARRICKS, OF SAN FRANCISCO, CALIFORNIA, ASSIGNOR OF ONE-HALF TO JESSE G. TUNNICLIFFE, OF SAME PLACE.

ELECTRIC AMALGAMATOR.

SPECIFICATION forming part of Letters Patent No. 669,058, dated February 26, 1901.

Application filed August 6, 1900. Serial No. 26,020. (No model.)

To all whom it may concern:

Be it known that I, LOUIS HENRY BARRICKS, a citizen of the United States, residing in the city and county of San Francisco, in the State of California, have invented an Improvement 5 in Electric Amalgamators; and I hereby declare the following to be a full, clear, and exact description of the same.

My invention relates to an improvement in 10 electric amalgamators.

It consists of electrolytic boxes having vertical porous partitions, pivotal sectional sluices, and supports adapted to an incline, whereby the boxes, riffles, and sluices may be 15 arranged in series, and of details of construction shown by the following drawings.

Figure 1 is a longitudinal vertical section. Fig. 2 is a detail sectional view of the sluice-box, trough, and connections. Figs. 3 and 4 20 illustrate detailed views of the anode and cathode.

A represents an incline of wood or iron. B represents supports or, as I term them, "knee-brackets," adapted to and secured upon this 25 incline and carrying upon their longer horizontal edges the solution and mercury troughs E, and their upper vertical portions having each as lot 2 and side and bottom set-screws 3 to take a journal-box Q. These brackets are 30 arranged in pairs.

C is a sluice-box having journals or pivots 4, attached to the sluice by bolts, as 11, and fitting the journal-boxes Q, which latter have set-screws 5, by which the journals 4 are 35 locked at the desired adjustment. In the bottom of the sluice is a metal plate or riffle having a lip D.

The sluice-box C, with journal-boxes Q in place, is set between a pair of brackets B 40 and Q, locked in position in 2 by the set-screws 3, the lower edge of the sluice resting on the box E and the lip D extending down into the mercury contained in E. The set-screws 5 and 3 allow the incline of the sluices to be 45 regulated in accordance with the head of water, weight of material, fall, &c.

I have shown a solution-box and mercury-reservoir E, having a vertical porous partition F, dividing it into the part 6, containing a saline solution, and the part 7, holding mercury. 50

As shown in Fig. 2, the bottom of the box is

channeled to receive the lower edge of the partition. The bottom of the box extends forward of the partition for a comparatively short distance and is then upturned to form 55 a vertical wall 20, which forms between itself and the partition a compartment of considerable vertical area exposed to the partition, and the upper edge of the wall 20 is extended horizontally at 22 and provided with a retaining-flange 23 to hold back the mercury of contact of shallow horizontal depth, and into which latter compartment the end of the lip D dips, as shown. I make the box in this manner for the reasons:

First. Either 6 or 7 may be recharged or inspected at any time without discontinuing the operation of the sluices or shutting off the water. This is important, as the salt is used rapidly, and it is necessary that more be added 70 to the solution from time to time.

Second. The shape of the reservoir or mercury riffle 7 gives large surface of contact with the pulp, metal, and water passing onto it from the sluices. It is immaterial as far as 75 this part of its efficiency is concerned how deep this reservoir may be, but it figures considerably in the amount of mercury necessary and consequent cost. Hence the lip 8 of this reservoir is made quite shallow.

Third. In the same manner and for the same reason I get a large surface of contact with the porous plate F and shallow horizontal depth, for in this case is wanted simply a large area of contact with the percolating salt solution for electrolytic purposes, as will be 85 shown.

The solution compartment or cell is insulated by glass or other suitable material on the bottom and three sides. It may also carry 90 an insulated cover to keep the solution clean. An anode of lead 9 or equivalent substance is placed in the solution-box 6, having suitable wire or other connections with a circuit. The porous plate F is hermetically sealed on 95 the sides and bottom to the box E.

The box E, I prefer to make of cast metal in the shape shown and having grooves, into which this porous plate is to be cemented. The box E is attached to the knee-brackets by 100 bolts, as at 10.

G is a spreader or sluice through which the

pulp or ore, with water, is conducted to the boxes C.

H is a tail-trough by which the tailings are led off into the sluices I.

5 The pulp or ore to be worked may be gold, silver, platinum, mercury, or such metals as are usually worked by electrolysis.

The plate D, forming the cathode, is insulated from all electric connection with the 10 part 6 except as through the mercury and porous partition.

In operation the sluices and troughs upon brackets are arranged in series upon an incline, as shown. Water carrying its suspended 15 material passes through G into the sluice C, over the copper plate D and on to the mercury riffle, and then on through succeeding sluices and over like mercury riffles, as many as may be necessary and desired. During 20 this operation a current of electricity continuously passes from the positive electrode in the cell 6, containing a saline solution, through the porous cell and mercury, to the negative electrode D. The saline solution, slowly percolating through the porous partition, comes 25 in direct contact with the mercury, where the salt is decomposed by the current and sodium is liberated in quantities proportionate to the current and the mercury purified and kept 30 active in the well-known manner of sodium amalgam.

Having thus described my invention, what I claim as new, and desire to secure by Letters Patent, is—

35 1. In an amalgamator, the combination with a sluice-box, of a box or receptacle including two compartments and a permeable partition separating one compartment from the other one of said compartments adapted to contain 40 a saline solution and the other mercury, said mercury-compartment having a horizontal extension from the upper edge of one of its walls and said extension having a retaining-flange to provide the compartment with an extended 45 surface of mercury contact of shallow depth.

2. In an amalgamator, the combination with a sluice-box, of a receptacle having a permeable partition dividing it into cells of unequal size one of said cells adapted to contain a saline solution and the other mercury said box having its bottom extended in front of the partition to form a mercury-chamber of shallow horizontal depth and extended surface of contact with the partition, and the upper edge 55 of said wall extended horizontally and flanged to form an extended surface of mercury contact with the pulp and of shallow vertical depth.

3. In an amalgamator, a compartment receptacle having a vertical porous partition between the two, one of said compartments adapted to contain mercury and the other a saline solution, a sluice-box located above the

receptacle and having an electrical conducting bottom plate, one end of which dips into 65 the mercury, an electrical conductor for the other compartment and journal pins and boxes by which the sluice is adjustably supported.

4. The combination with a receptacle having a vertical porous partition forming two compartments one adapted to contain a saline solution and the other mercury, a sluice having an electrical conducting bottom dipping into the mercury-compartment, a conductor within the first-named compartment, journals and pins upon which the sluice is supported, and screws by which the journal-boxes are adjusted and the sluice-supporting pins locked. 80

5. In an amalgamator, the combination of an inclined frame with a series of brackets, and vertically-separated mercury and solution chambers carried thereon, each lower than the next preceding, of intermediate electrical conducting-plates the discharge ends of which dip into the succeeding mercury-chambers, electrical conductors in the solution-chambers and supports for said plates carried by and adjustable upon the brackets. 90

6. In an electrical amalgamating device the combination of a series of receptacles each having a permeable partition forming two compartments one adapted to contain a saline solution and the other mercury, an inclined 95 plane, and supports or knee-brackets attached thereto, pivoted and adjustable sluices having electrical conducting-bottoms dipping into the mercury-compartment and a conductor within the other compartment. 100

7. In an electric amalgamator, the combination of an inclined plane, supports attached thereto carrying upon their horizontal edges a vertically-partitioned amalgamating-trough forming two cells one adapted to contain a saline solution and the other mercury, and one of said cells having an extended shallow end, vertical extensions of these supports or brackets above the trough, journal-boxes adjustably fitted thereto, a sluice-box having 110 journals near one end fitting these journal-boxes, means for adjusting the incline of the sluice-box, a metal plate within and projecting beyond the sluice-box, and dipping into the mercury-containing cell, said plate forming the cathode and electrically connected with the anode within the solution-containing cell through the porous partition and contacting fluids. 115

In witness whereof I have hereunto set my hand.

LOUIS H. BARRICKS.
